CLAIM

We claim the ornamental design for a helmet, as shown and described.

DESCRIPTION

FIG. 1 is a front view of a helmet, showing our new design; FIG. 2 is a rear view thereof; FIG. 3 is a top plan view thereof; FIG. 4 is a bottom view thereof; FIG. 5 is a right side view thereof; FIG. 6 is a left side view thereof; FIG. 7 is a front perspective view thereof; and, FIG. 8 is a rear perspective view thereof. The details shown in broken lines form no part of the claimed design.
